UNITED STATES PATENT OFFICE.

MAURICE L. POWERS, OF NEW YORK, N. Y.

DESIGN FOR A FINGER-RING.

SPECIFICATION forming part of Design No. 24,089, dated March 12, 1895.

Application filed February 9, 1895. Serial No. 537,834. Term of patent 3½ years.

To all whom it may concern:

Be it known that I, MAURICE L. POWERS, a citizen of the United States, and a resident of New York, in the county of New York and State of New York, have invented a certain new and useful Design for Finger-Rings, of which the following is a specification, reference being had to the accompanying drawing, which shows a perspective view of a finger-ring embodying my design.

The leading feature of my design consists in the representation upon each side of the setting of a finger ring, the crown or equivalent of the setting, of horses' hoofs, *a*, *a*, presented bottom upward, and outwardly to view, and having each a shoe, *b*, *b*, thereon. The ring adjacent to the hoofs is chased, embossed or otherwise treated, as at *c*, *c*, to give the semblance of the hair on a horse's fetlock.

The shoes are represented as fastened to the hoofs by nails; the heads, *d*, *d*, of which are simulated by preciousstones (or chips thereof) or by an ornamentation in the metal of the shoe, which presents a similar outward effect.

As above stated, the space between the hoofs is decorated in any suitable manner, as shown.

I claim—

The design for a finger ring herein shown and described.

Signed at New York, in the county of New York and State of New York, this 5th day of February, A. D. 1895.

MAURICE L. POWERS.

Witnesses:

D. S. RITTERBAND,
W. J. FARRELL.
